UNITED STATES PATENT OFFICE.

STEPHEN D. FIELD, OF NEW YORK, N. Y., ASSIGNOR TO THE COMMERCIAL TELEGRAM COMPANY, OF SAME PLACE.

PRINTING-TELEGRAPH.

SPECIFICATION forming part of Letters Patent No. 290,557, dated December 18, 1883.

Application filed August 27, 1883. (No model.)

To all whom it may concern:

Be it known that I, STEPHEN D. FIELD, of New York, in the county of New York and State of New York, have invented a new and useful Improvement in Printing-Telegraphs; and I do hereby declare that the following is a full and exact description of the same, reference being had to the accompanying drawings, and to the letters of reference marked thereon.

My invention relates to that class of "step-by-step" or "gold and stock" printing-telegraphs in which two type-wheels are used from which a record is made on one fillet or band of paper in two parallel lines; and its object is to furnish a novel, simple, and reliable means for determining at will which one of the two type-wheels shall be printed from. Each type-wheel is supported on its own shaft, which carries an escape-wheel controlled by an anchor. Both anchors are upon the same shaft, controlled by the armature of one polarized electro-magnet in the main type-wheel circuit. A motor is provided tending normally to rotate continuously both type-wheels, which tendency to continuous rotary motion is regulated and changed by the anchor and escapement noted into a step-by-step or intermittent rotary motion. Thus far the construction is the same as in Letters Patent No. 274,300, granted me March 20, 1883, the difference being in the means employed for determining which wheel shall be printed from, while the other is held in such position that no impression therefrom is had. Each wheel is provided with a blank or unison point, where, if the paper be impressed thereat, no record is made. An organization is provided to always hold one of the wheels at that point, while the other is allowed to rotate and be positioned for printing. In the type-wheel circuit is placed an ordinary or neutral electro-magnet, with an ordinary armature, armature-lever, and retractor. The armature-lever at its free end is connected to a bar at a right angle. To this bar are loosely or pivotally attached two uprights, the mode of attachment being such that the uprights may have a limited vertical play or movement. These uprights have lugs or projections upon their inner sides in such position that the lever of the printing-magnet shall always, when

called into action, cause devices connected therewith, to be hereinafter described, to strike upon one or the other lug and carry up with it the corresponding upright. The uprights at their upper ends are pivoted to the ends of a rocking bar, hung at its center upon a shaft supported in the framing of the instrument. From this shaft projects downwardly and outwardly, on opposite sides, two arms, the ends of which, when properly positioned, may take against stops placed in the escapement, there being one arm for each escapement. Thus as one or the other upright is carried up by the devices connected with the printing-magnet, the shaft is rocked and one or the other arm positioned to come into contact with the stop in the proper escapement and lock it against the stress of the motor, the other escapement being simultaneously released and allowed to operate. This may be more clearly understood from the following detailed description, and from the drawings, in which—

Figure 1 is a perspective of the parts embodying the invention, and Fig. 2 is a front view of the extra magnet and attachments for determining which wheel shall be rotated and positioned for printing.

The framing, paper-feed, inking devices, motive power, &c., forming no part of this invention, and being well known to those skilled in the art, are omitted from the drawings, in order that the real matters of invention may be more clearly shown, it being well understood that in practice they will be supplied in any of the well-known and usual ways.

A is a polarized electro-magnet in the type-wheel circuit 11, and having an armature, a, attached to a vibrating or rocking shaft, B, carrying anchors b b'.

D E are two type-wheels, each having its own set of characters, its own shaft, and escape-wheel, D being on the shaft C with the escape-wheel d, and E on shaft C' with escape-wheel d', the anchor b meshing with and controlling d, while b' meshes with and controls d'. A motive power (not shown) is common to and tends normally to actuate both C and C' through pinions c c'.

In the printing-circuit 22 is the printing or press magnet P, having armature p, retractor f', and armature-lever PL, carrying the platen

or press P' , of sufficient size to take upon either wheel D or E .

I is an ordinary electro-magnet in the circuit 11, provided with armature and armature-lever J and retractor j . At its upper end the lever J is connected to an arm, H , arranged to slide in any well-known and suitable manner. To H are attached the uprights F F' , the attachment being one which will permit 10 limited vertical play or movement of F F' , which is here accomplished by means of pins passing through slots in F F' into the body of H . F F' are provided with lugs or projections f f' upon their inner edges. At their 15 upper ends, F F' are pivoted to a cross-arm, G , hung at its center upon a shaft, g , suitably supported in or from the framing of the instrument.

At points upon shaft g , in contiguity to the 20 escape-wheels d d' , are arms t t' , projecting downwardly in opposite directions, their ends being formed into hooks or stops, as shown. Upon each escape-wheel d d' is a stop, o , the stops o and the arms t t' being so positioned 25 relatively to each other that whatever be the position of the rocking arm G and shaft g one of the stops will take against one of the arms t t' , while the other stop is free from its arm.

Attached to the printing-lever P L is an arm 30 or shaft, R , to which is attached at right angles a second arm, U , provided with lugs i i , arranged so that one or the other will always take under the lugs f f' on the uprights before mentioned; hence whenever the printing-lever 35 is operated the arm U will be likewise operated and control the position, through uprights F F' , of the shaft g and arms t t' .

The retractor j of armature J is so adjusted 40 that normally a strong current is needed to overcome its resilience and permit I to attract J , so if a current less than a normally-strong one be used, j will hold J against the attraction of I .

The transmitter (which forms no part of 45 this invention, and hence is not herein illustrated) is so arranged that when stopped to position one wheel it holds the circuit 11 closed with normal full strength, while when stopped to position the other wheel it holds the circuit 50 11 either broken or closed, with a current of so much less than normal strength that I does not overcome the force of j . Supposing, now, that the wheel E has been in use, has been positioned, and printed from. During such operation 55 the stop t has contacted with o on d , held D against rotation, and in such position that the blank space of the type-wheel D was opposite P' , so that no impression could be made therefrom. A change to D is now to be made. The 60 transmitter is turned to bring E to blank and

stopped, with the circuit 11 closed. The force, then, of I holds J to itself. The printing-circuit 2 2 is now closed and the armature-lever P L thrown up, carrying with it the shaft R and arm U , the lug i on the latter striking f 65 on F , lifting it, and thereby turning G and its attached shaft g , so as to swing t on its shaft g clear of o on d and place t' in the path of o on d' . The transmitter being then used, D is free to rotate, be positioned, and printed from, as 70 long as desired.

When desired to change to E , the circuit 11 is either weakened or is left open with the wheels brought to blank and the circuit 2 2 actuated, when i strikes f on F' , lifting it, de- 75 pressing F , and causing t to be swung into the path of o on d .

By these means one or the other of the two type-wheels and its escapement is certainly and readily locked at will against the stress of the 80 motive power, and in position to give no impression, while the other is allowed to be freely rotated by the motive power as controlled by the escapement and be positioned and printed from. 85

I do not claim herein the combination of two type-wheels, each mounted on its own shaft, two escapement mechanisms—one for each wheel—a mechanism adapted to simultaneously lock one type-wheel and unlock the 90 other, and a magnet in the escapement-circuit for positioning the locking and unlocking mechanism to be properly acted on by the printing mechanism; but

What I do claim herein, and desire to secure 95 by Letters Patent, is—

1. The combination, in a printing-telegraph, of two type-wheels, two escapements, one for each wheel, each provided with a lug or stoppin, a polarized magnet controlling both escapements, a neutral magnet in the escapement-circuit, and a rocking shaft controlled thereby and carrying two arms adjusted and adapted so that one arm takes upon and contacts with the stop upon one escapement, while the 105 other arm is freed from the stop upon the other escapement, substantially as set forth.

2. The combination, in a printing-telegraph, of two type-wheels and their respective escapements, each provided with a lug or stoppin, of the shaft g , carrying arms t t' , the cross-arm G , attached to g , the uprights F F' , and arm U , and shaft R , operated by the printing-lever, substantially as set forth. 110

This specification signed and witnessed this 115 24th day of August, 1883.
